To All to whom these letters patent shall come:

Whereas John Moon a Citizen of the United States hath alleged that he has invented a new and useful improvement in his Machine for Shelling Corn which improvement he states has not been known or used before his application hath affirmed that he does verily believe that he is the true inventor or discoverer of the said improvement hath paid into the treasury of the United States the sum of thirty dollars delivered a receipt for the same and presented a petition to the secretary of state signifying a desire of obtaining an exclusive property in the said improvement and praying that a patent may be granted for that purpose these are therefore to grant according to law to the said John Moon his heirs Administrators or Assigns for the term of fourteen years from the Twenty second day of June one thousand eight hundred and twenty five in the full and exclusive right and liberty of Making constructing using and lending to others to be used the said improvement a description whereof is given in the words of the said John Moon himself in the schedule herunto annexed and is made a part of these presents for testimony whereof I have caused these letters

Letters to be made patent and the seal of the United States to be hereunto affixed

Given under my hand at the city of Washington this twenty seventh day of June in the year of our Lord one thousand eight hundred and twenty five and of the independence of the United States of America the forty ninth

J. Q. Adams.

By the President

H. Clay Secretary of State
City of Washington D. C.

I do hereby certify that the foregoing letters patent were delivered to me on the twenty seventh day of June in the year of our Lord one thousand eight hundred and twenty five to be examined that I have examined the same and find them conformable to law and I do hereby return the same to the Secretary of State within fifteen days from the date aforesaid to wit this twenty seventh day of June in the year aforesaid

W. W. West

Attorney General of the United States
